UNITED STATES PATENT OFFICE.

DAVID ALLEN AINSLIE, OF RICHMOND, VIRGINIA.

TROLLEY FOR ELECTRICAL RAILWAYS.

SPECIFICATION forming part of Letters Patent No. 400,724, dated April 2, 1889.

Application filed April 12, 1888. Serial No. 270,429. (No model.)

To all whom it may concern:

Be it known that I, DAVID ALLEN AINSLIE, a citizen of the United States, residing at Richmond, in the county of Henrico and State of Virginia, have invented certain new and useful Improvements in Trolleys for Electrical Railways, of which the following is a specification.

My invention relates to a device for use on cars equipped with an electric motor, and is designed to make connection with the elevated wire on which the electric current runs. The device is termed a "trolley."

The accompanying drawings illustrate the invention.

Figure 1 is a side view of the device and its support as it appears on the roof of the motor-car. Fig. 2 is a side view as seen in a transverse direction from that shown in Fig. 1. Fig. 3 is a horizontal section on the line 3 3.

The trolley consists of a brass cylinder, A, having journalized ends b, which fit in bearings on two brass arms, B, which are attached to an upright staff or bar, C. Practically the said two arms B are mere bifurcations at the upper end of the said staff. The trolley-cylinder has a central groove, d, around it which comes in contact with and receives the overhead wire, (not shown,) along which the electric current runs.

A leading object of the invention is to so construct and mount the trolley-staff C as to afford it swinging movement in all directions and to provide for its self-adjustment, to the end that while the cylinder A will be maintained in a horizontal position, and thereby keep contact with the overhead wire, it will not hang or catch or break the said wire.

The staff C is made in two sections—the lower one, a, and the upper one, a'. The lower one is pivoted at e, and above the said pivot the two sections are united by a joint or hinge, l. To retain the top section, a', in an upright position, one or more suitable springs are employed at the said hinge. One form of spring is here shown, and consists of a wire having a coil-bend, n, at its center and the coil-bend located at the hinge l, and the two ends, o, projecting in opposite directions, each end o being attached at p to a different

section of the staff. Two such springs are here shown, one being at one side and the other at the opposite side. By this means the top section, a', carrying the cylinder, may yield at the joint or hinge l.

The trolley-staff has a pivot-bolt, e, and is pivoted within a metal ring or collar, f, which has pivots g at diametrically-opposite points which are on a line at right angles with the pivot-bolt e. The ring f is mounted in the present instance in a supporting-ring, H, which is fixed at the upper end of standard I. It will be seen that this construction for mounting the staff C is a gimbal-joint, which provides for a pivoting movement in all directions. The bottom of the trolley-staff has a weight, k, which serves to maintain the trolley in its normal position, while the gimbal-joint affords the desired movement. A readily-yielding spring, q, connects the lower end of the staff or the weight with the top r of the car. While the spring q will aid in retaining the staff C in the normal upright position, it will yield readily to allow the staff to be tilted on the gimbal-joint. The trolley-cylinder A and supporting-arm B are kept in electric connection with the motor on the car by a wire, s, attached to the said arms, and from thence passing through an eye or guide, t, to the motor on the car.

From the foregoing the operation of the device will be readily understood.

Having described my invention, I claim—

1. A trolley for electric-motor cars, comprising the combination of a standard, I, provided at its top with a gimbal-ring, a staff mounted on a pivot in said gimbal-ring with its lower end free, so as to have a swinging movement in all directions, and a cylinder on the upper end of the staff.

2. A trolley for electric-motor cars, comprising the combination of a staff made in two sections which are united by a spring-joint, a supporting-pivot attached to the lower section, and a cylinder on the upper end of the top section.

3. A trolley for electric-motor cars, comprising the combination of a staff made in two sections, which are united by a joint or hinge, a supporting-pivot attached to the

lower section, a spring at the said joint or hinge to retain the top section upright, and a cylinder on the upper end of the top section.

4. A trolley for electric-motor cars, comprising the combination of a staff made in two sections which are united by a spring-joint, a gimbal-ring supporting the said staff, and a cylinder on the upper end of the top section.

10 5. A trolley for electric-motor cars, comprising the combination of a gimbal-ring, a staff mounted on a pivot in said gimbal, so as to have a swinging movement in all directions, a cylinder on the upper end of the staff, 15 and a weight attached to the bottom of the staff.

6. A trolley for electric-motor cars, comprising the combination of a gimbal-ring, a staff mounted on a pivot in said gimbal, so as to have a swinging movement in all directions, a cylinder on the upper end of the staff, a weight attached to the bottom of the staff, and a spring connecting the lower end of the weighted staff with the car-top.

In testimony whereof I affix my signature in 25 the presence of two witnesses.

DAVID ALLEN AINSLIE.
